JET POWERED REMOTELY PILOTED VEHICLE

Leroy I. Sather, 2532 14th W., Seattle, Wash. 98119

Filed Aug. 25, 1971, Ser. No. 175,029

Term of patent 3½ years

Int. Cl. D22—03

U.S. Cl. D22—11

FIG. 1.

FIG. 2

FIG. 3

FIG. 4

FIG. 5

FIG. 6

FIG. 1 is a top plan view of a jet powered remotely piloted vehicle;

FIG. 2 is a front elevational view of said vehicle;

FIG. 3 is a bottom plan view of said vehicle;

FIG. 4 is a rear elevational view of said vehicle;

FIG. 5 is a side elevational view of a first side of said vehicle; and,

FIG. 6 is a side elevational view of the other side of said vehicle.

I claim:

The ornamental design of a jet powered remotely piloted vehicle, substantially as shown.
